ABSTRACT

A container having base and lid sections, one of which has a wall member dimensioned to be surrounded by and nested within the wall member of the other section when the container is closed. The container further includes hinge means providing a pivotal connection between the wall members of the base and lid sections. The hinge means defines a pivotal axis which, during opening and closing of the container, is movable laterally relative to one section while being fixed against lateral movement relative to the other section.

CROSS REFERENCE TO RELATED APPLICATION

This application is a continuation-in-part of U.S. Application Ser. No. 122,566 filed Mar. 1, 1971 now 5 abandoned.

DESCRIPTION OF THE INVENTION

This invention relates to a container made up of base and lid sections which are in a nested relationship when the container is closed, and which are hingedly connected to permit pivotal movement of one section relative to the other about an axis which moves laterally in relation to only one of the sections when opening and closing the container.

A general object of the present invention is the provision of a more attractive container, wherein base and lid sections are pivotally connected by hinge means which remain hidden from exterior views regardless of whether the container is open or closed. Another object of the present invention is to provide, in conjunction with a container having base and lid sections which are nested when the container is closed, hinge means which permit the container to be opened by pivotally moving one section relative to the other about an axis which is movable laterally in relation to only one of the container sections. A further object of the present invention is to provide means for pivotally connecting the base and lid sections of a container, which means permits the said sections to be nested one within the other when the container is either opened or closed.

These and other objects and advantages of the present invention will become more apparent as the description proceeds with the aid of the accompanying 35 drawings, wherein;

FIG. 1 is a perspective view of one embodiment of a container embodying the concepts of the present invention, the container being closed with the base section nested within the lid section;

FIG. 2 is another perspective view showing the container of FIG. 1 open;

FIGS. 3 and 3A are sectional views taken along lines 3-3 and 3A-3A of FIG. 1 with the interior liner removed;

FIG. 4 is an exploded perspective view of the base and lid sections of the container shown in FIGS. 1-3A, with portions cut away to better illustrate details of the hinge means;

FIGS. 5A-5D are schematic illustrations of the relative movement and cooperative relationship between the container components when the container is opened;

FIG. 6 is a perspective view showing a slightly modified form of the invention with the base section fully nested within the lid section when the container is open;

FIGS. 7A-7E are schematic illustrations of the relative movement and cooperative relationship between the container components of the embodiment shown in FIG. 6;

FIG. 8 is a sectional view similar to FIG. 3 showing another embodiment of the invention;

FIG. 9 is an exploded perspective view showing details of the embodiment illustrated in FIG. 8;

FIG. 9A is an end view of the base section taken along lines 9A-9A of FIG. 9; and,

2

FIGS. 10A-10D are schematic illustrations of the relative movement and cooperative relationship between the container components of the embodiment shown in FIGS. 8-9A.

A more detailed description of the invention will now be provided with initial reference to FIGS. 1-4 wherein a container generally indicated at 10 is shown comprising base and lid sections 12 and 14. The lid section 14 includes a wall member 16 which is of a generally rectangular configuration having oppositely disposed pairs of straight parallel ends and sides 16a and 16b. Wall member 16 is further provided with flanges 18a and 18b extending inwardly from the upper and lower edges thereof, with flange 18a preferably being wider than flange 18b. A planar element 20 is surrounded by wall member 16. As is best shown in FIGS. 3 and 3A, planar element 20 is provided with opposed integral flaps 22a and 22b which are bent downwardly at an angle of approximately 90°. These flaps, which are hereinafter at times referred to as "insert members", cooperate with the wall flanges 18a and 18b to wedge the planar element 20 in place as shown in the drawings. If desired, the flaps or insert members 22a and 22b may be made up of one or several strips which are separate from rather than integral with planar element 20. As is best shown in FIGS. 3 and 4, elongated slots 24 are provided between the lower edges of the insert members 22b and the lower wall flanges 18b.

Base section 12 includes a second wall member 26 which is also made up of oppositely disposed ends and sides 26a and 26b defining a rectangular configuration which is suitably dimensioned to nest within the wall member 16 of the lid section 14 when the container is closed, as shown in FIG. 1. Wall member 26 has upper and lower inwardly disposed flanges 28a and 28b, the latter serving as a support for a second planar element 30. Element 30 is held in place by insert members 30a and 30b, which again may either be integral with or separate from element 30.

The base section 12 is connected to lid section 14 by hinge means including a pair of hinge elements generally indicated at 32. Each hinge element is generally U-shaped in cross-section, having a pair of parallel legs 32a and 32b joined at one end by a web section 32c. The legs 32a and 32b need not be of equal length, it being preferable to have leg 32a the longer of the two. With respect to each hinge element 32, the web section 32c extends laterally across one of the slots 24 formed between the insert member 22b and the lower wall flange 18b. The leg 32a is located between an insert member 22b and the interior surface of the wall member 16a, and the other leg 32b is located between the insert member 22b and the adjacent exterior surface of the side 26a of wall member 26. Leg member 32b is further provided with an integral pintle 34 which protrudes laterally into a suitably dimensioned receiving hole 36 in the adjacent side 26a of the base section wall member 26. The insert members 30b are also preferably indented or apertured as at 38 to accommodate the pintles 34.

In view of the foregoing, it will now be seen that base section 12 is pivotally connected to the hinge elements 32 by means of the laterally extending pintles 34, and the hinge elements are in turn mounted on the wall assembly of the lid section 14. The hinge elements are slidably movable along the lengths of the wall ends 16a

through a distance which is defined and limited by the lengths of slots 24.

The relative movement and cooperative relationship between the components described above will now be further illustrated with reference to FIGS. 5A-5D. In FIG. 5A, the container is schematically depicted in the closed condition, as shown also in FIGS. 1, 3 and 3A, with the base section 12 nested within the lid section 14. When the base and lid sections are thus arranged, the hinge elements 32 are located at one end (the left end as viewed in FIGS. 5A-5B) of slots 24, and the pintles 34 are aligned along a pivotal axis "a" extending in a direction transverse to the slots 24. As is further depicted in FIGS. 5B-5C, when opening the container, the lid section 14 is pivoted about axis "a" in the direction indicated by arrow "b" relative to the base section 12. This pivotal motion is accompanied by movement of the hinge elements 32 along the slots 24 as schematically depicted by arrows "c". FIG. 5D shows the limit to which the respective components may be manipulated to place the container in the full "open" condition. At this stage, the hinge elements 32 have moved to the opposite ends of the slots 24. The lid section 14 is in contact with the base section 12 as at 40 and 42, and the open container may thus be supported on a flat surface 43 at 44 and 46. The container may be closed by simply reversing the above steps. It will thus be seen that when opening or closing container 10, the pivotal axis "a" is allowed to move laterally relative to the lid section 14 while being prevented from moving laterally relative to the base section 12.

FIGS. 6 and 7A-7E illustrate a slightly modified form of the invention, wherein a container 10' is again shown comprising base and lid sections 12' and 14', each having the same basic construction as that of the base and lid sections 12 and 14 shown in FIGS. 1-5. Base and lid sections 12' and 14' are pivotally connected by hinge elements 32', the only difference being that the slots 24' extend along the full lengths of the end walls on the lid section 14'. When container 10' is closed as schematically depicted in FIG. 7A, the base section 12' is again nested within lid section 14', and the hinge elements 32' are located at one end (the left end as shown in FIGS. 7A-7B) of slots 24'. When the container is opened, the lid section 14' is again pivoted in the direction indicated by arrow "b" relative to the base section 12'. This pivotal motion is accompanied by sliding movement of the hinge elements 32' along slots 24' in the direction of arrow "c". However, the lengths of slots 24' permit the lid section 14' to be pivoted through approximately 360° in a counterclockwise direction relative to base section 12, with the result that when the container is fully opened as shown in FIGS. 6 and 7E, the base section 12' is again nested in the lid section 14', with the latter now being in the inverted position.

Referring now to FIGS. 8 to 9A, there is shown another embodiment of the invention wherein the container 10" is again comprised of a base section 12" and a lid section 14". The base section has a bottom planar element 48 with side walls 50a and end walls 50b which may conveniently although not necessarily be formed as a metal stamping. The base section is usually covered with decorative sheet material 52 held in place by an adhesive.

The lid section 14" is comprised of a metal rim 54 having end and side walls 54a and 54b and further in-

cluding upper and lower inwardly extending flanges 56a and 56b. A top planar element 58 is held against the upper rim flange 56a by planar insert means 60, the latter being wedged between the top planar element 58 and the bottom rim flange 56b. Depending on the relative depths of the base and lid sections 12" and 14", it may also be desirable to employ a second insert 57 with a downturned lip portion 57a. The purpose of lip portion 57a will hereinafter become apparent as the description continues.

The base and lid sections 12" and 14" are connected by hinge means generally indicated at 62 in FIG. 8. The hinge means includes a pair of hinge elements 64 (see FIGS. 9 and 9A), each having a generally U-shaped cross section with inner and outer legs 64a and 64b joined by an intermediate web section 64c. The inner leg 64a is further provided with an inturned lip 64d which engages the inside surface of the base section end wall 50a. The outer leg 64b has a laterally extending pindle 66 which protrudes into a slot 68 in the adjacent insert means 60 of the lid section 14". As is best shown in FIG. 9, the slot 68 is preferably although not necessarily inclined at an angle.

It will be understood that the hinge elements 64 are clamped in fixed positions to the end walls 50a of the base sections 12", with the pintles 66 aligned to provide a pivotal axis schematically indicated at "a".

The relative movement and cooperative relationship between the components illustrated in FIGS. 8 to 9A will now be further illustrated with reference to FIGS. 10A-10D. In FIG. 10A the container 10" is schematically depicted in the closed condition, with the base section 12" nested within the lid section 14". When the base and lid sections are thus arranged, the pintles 66 of the hinge elements 64 are located at one end (the upper left end as shown in FIG. 9 and 10A) of the slots 68. Also, the top front edge of the base section is in contact with the lower edge of the lip 57a on the insert 57 of the lid section 14". This latter relationship maintains the planar surfaces 58 and 48 parallel. As the container 10" is opened, the base and lid sections 12" and 14" are pivoted in relation to each other about an axis "a". In addition, the pintles 66 are caused to move along the slots 68. FIG. 10D shows the limit to which the respective components may be manipulated to place the container in a full open condition. The container may be closed by reversing the above steps.

In light of the foregoing description, it will now be appreciated by those skilled in the art that the present invention embodies several unique and advantageous features, among which is the provision of a container assembly having hingedly connected base and lid sections which may be arranged in a nested relationship when the container is closed. This is accomplished by providing hinge elements with laterally extending pintles aligned to define a pivotal axis. The hinge elements may be movably mounted on the end walls of one of the sections, as with the embodiments shown in FIGS. 1 to 7E, in which case the pintles will protrude laterally into holes in the adjacent end walls of the other section. Alternatively, the hinge elements may be fixed to the end walls of one section, as with the embodiment shown in FIGS. 8-10D, in which case the pintles will protrude into slots in the end walls of the other section. In all cases, however, the pivotal axis "a" defined by the pintles of the hinge elements is movable laterally in relation to only one of the container sections.

A further advantage of the invention is the provision of hinge means which remain hidden from exterior view, regardless of whether the container is open or closed.

While the invention has been described above in conjunction with box-like containers, it will be understood that the same concepts will apply equally as well to frame-type containers, such as for example picture frames. Also, it is to be understood that although the pintles have been shown formed on hinge elements which are separable from the container sections, under certain circumstances it may be advantageous to mold the pintles into one container section and to mold the pintle receiving apertures or slots into the other section.

It is our invention to cover these and any other changes and/or modifications of the embodiments herein chosen for the purposes of disclosure which do not depart from the spirit and scope of the invention.

We claim:

1. A container comprising in combination: base and lid sections suitably dimensioned to be nested one within the other when the container is closed, each of said sections having spaced oppositely disposed straight parallel side walls; a pair of generally U-shaped hinge 25

elements, each of which includes laterally spaced legs interconnected at one end by an intermediate web, one of the legs on each of said hinge elements having a pintle extending laterally therefrom, said hinge elements being mounted in oppositely disposed relationship on the side walls of one of said sections, with the legs of each hinge element straddling the side wall on which the hinge element is mounted and with the pintles of both hinge elements aligned axially; receiving means on the side walls of the other of said sections for receiving said pintles in axial insertion therein, said hinge elements cooperating with said receiving means during opening and closing of said container to permit pivotal movement of one section relative to the other about the axis defined by said pintles while at the same time permitting lateral movement of said axis relative to one of said sections.

2. The container as claimed in claim 1 wherein said hinge elements are fixed in relation to the side walls on which they are mounted, and wherein said receiving means comprise elongated slots.

3. The container as claimed in claim 1 wherein said hinge elements are movable along the lengths of the side walls on which they are mounted.
